TOWEL PACKAGE

Isaac Gindi and Jack Ashkenazie, Brooklyn, N. Y.

Application July 29, 1954, Serial No. 31,649

Term of patent 3½ years

(Cl. D58—12.6)

Fig. 1

To all whom it may concern:

Be it known that we, Isaac Gindi and Jack Ashkenazie, both citizens of the United States of America, both residing at Brooklyn, in the county of Kings and State of New York, have invented a new, original, and ornamental Design for a Towel Package, of which the following is a specification, reference being had to the accompanying drawing, forming a part hereof.

Fig. 2 is a side perspective view thereof.

We claim:

The ornamental design for a towel package, substantially as shown.
